TETHERING DEVICE FOR AIRPLANES

James Martin, Higher Denham, near Uxbridge,
EnglandApplication July 21, 1945, Serial No. 606,357
In Great Britain August 7, 1944

5 Claims. (Cl. 244—115)

1

This invention relates to tethering an aeroplane on the ground whilst the engine is being run for testing or tuning purposes or during preliminary running-up of the engine preparatory to the aeroplane taking off from an aerodrome or other place. It is the usual practice when testing or running-up the engine of an aeroplane to place wooden or other chocks in front of the landing wheels of the aeroplane in order to prevent it from moving on the ground owing to the thrust produced by rotation of the airscrew or airscrews. Owing to the steady increase of engine power and to the increased thrust produced by variable pitch and contra-rotating airscrews, this method is no longer satisfactory and this applies more particularly to aeroplanes of the high speed fighter type. It is found that there is an increasing tendency for the aeroplane to jump the chocks when the engine is run up to anything like full throttle or maximum revolutions, with a consequent danger of damage to the aeroplane and of injury to the pilot or tester in the aeroplane and other mechanics or onlookers in the neighborhood. The object of this invention is to provide a more reliable and positive method of anchoring or tethering an aeroplane on an aerodrome or other place.

According to this invention a single tethering member is securely anchored and fixed in the aerodrome, runway, testing shed or other place, a swivelling connection is provided on the tethering member for securing one or more cables adapted to be connected to forward parts of the aeroplane to take the forward thrust and a further connection from the tethering member extending upwardly to the tail end of the aeroplane to restrain its tendency to lift. It is preferred to provide a socket firmly anchored in the aerodrome or other place and a base pillar is fitted thereto. An attachment plate swivels about the base pillar and two tethering cables are connected to the plate and are provided at their forward ends with readily releasable connections for securing to suitable parts of the aeroplane such as the landing wheel axles, the undercarriage legs or the wings. These cables take the forward thrust when the engine is running and enable the aeroplane to face in any direction round the tethering member. A link extends upwardly from the base pillar to a readily releasable connector by which it is secured to the tail end of the aeroplane to control the lift thereof, and means may be provided for adjusting the effective length of the link.

In order that the invention may be more readily understood, examples showing how it may be carried into effect will now be described with reference to the accompanying drawings, in which

Fig. 1 is a perspective view of a fighter type

2

of aeroplane showing diagrammatically how it is tethered according to this invention.

Fig. 2 is a perspective view of a cage for anchoring in the ground and provided with a socket adapted to receive the base pillar.

Fig. 3 is a part sectional elevation showing an alternative type of socket and also the base pillar and swivel plate for the tethering cables.

Fig. 4 is a perspective view of one of the undercarriage landing wheels showing how the tethering cable may be attached to its axle.

Fig. 5 is a part sectional plan showing the forward end of the tethering cable secured to a swivel plate on the end of the axle of an undercarriage landing wheel.

Fig. 6 is a perspective view showing in detail the base pillar with connections for the two forwardly extending tethering cables and the upwardly extending cable for connection to the rear end of the fuselage of the aeroplane and including means for adjusting the effective length of the upwardly extending cable, and

Fig. 7 is a detail showing an alternative adjusting means for varying the effective length of the upwardly extending cable.

Referring to Fig. 1 of the drawings the aeroplane 1 is tethered by two tethering cables 2 secured at their forward ends to the axle ends 3 of the landing wheels 4. The dot and dash lines indicate alternative positions for tethering cables 2a which may be secured to the undercarriage legs 4 or even higher up close to their point of attachment to the wings of the aeroplane. The other ends of the tethering cables 2 or 2a are secured to a plate which may swivel about a base pillar secured in a socket 5 anchored in the ground by a cage 6 into which it is built. A further upwardly extending cable 7 extends from the base pillar in the socket 5 and is connected to a fitting 8 secured to a strong part of the fuselage frame. If however the fuselage is of monocoque construction, then the cable 7 may be connected to a sling 9 (shown in dot and dash lines) which is passed round the fuselage.

The construction of the cage 6 is shown in Fig. 2. This is intended primarily for anchoring the socket 5 in ordinary open ground such as a field or common or on desert or sandy beaches which it is required to use as a temporary or emergency aerodrome. The cage 6 is built round a central tube 10 having flanges 11 at its two ends and the socket 5 is fitted in the upper end of the tube 10. The cage comprises upper and lower rectangular frames 12 and 13 formed of angle iron and connected to the flanges 11 at the two ends of the tube 10 by the radial members 14. The two frames 12 and 13 are connected together by corner posts 15 and the whole structure is stiffened by the diagonal stays 16. The cage is of a suffi-

cient size so that when a suitable hole is dug in the ground and the cage is placed in position in it and the material removed in digging the hole is again filled into it and firmly rammed, then the cage will be so firmly secured that it will withstand the maximum thrust or lift which could possibly be exerted on it by any aircraft intended to be tethered thereto.

An alternative form of anchorage for the socket 5 is shown in Fig. 3. This arrangement is intended mainly for use in permanent aerodromes, runways or testing sheds and comprises a strong tube 20 of any suitable length which is set vertically in concrete 21 and has any suitable number of transverse rods 22 passed through the tube and projecting laterally into the concrete so as to secure a firm anchorage of the tube 20 in the concrete. The top of the socket 5 which is welded into the tube 20 is preferably located in a shallow recess in the ground so that the base pillar 23 when fitted in the socket 5 does not project much above normal ground level. The base pillar 23 is provided with a shank 24 the upper part of which is a close fit in the plain bore 25 of the socket 5 whilst the lower end of the shank 24 is screw threaded and is screwed into the lower screw threaded part of the bore 25 in the socket 5. The upper part of the base pillar 23 (shown also in Fig. 6) has a hexagonal part by which it may be screwed firmly into the socket 5. On the bearing 26 is fitted the swivel plate 27 the bore 28 of which is radiused to allow the swivel plate to align itself with the tethering cables 2. The tethering cables 2 are each fitted with a forked cable end 29 the shank 30 of which is swaged onto the end of the cable and the forked end of each is pivoted to the swivel plate 27 by a pivot bolt 31. The swivel plate 27 is retained in position by a collar 32 clamped against a shoulder 33 by a nut 34. The length of the bearing 26 is greater than the thickness of the swivel plate 27 so as to permit the swivel plate to rock on the bearing 26 to a limited extent to line up with the direction of pull on the cables 2.

On the top of the base pillar 23 are formed the two lugs 35 bored to receive the pivot bolt 36 which passes through them and the block 37 (see Fig. 6). To this block are secured the perforated links 38 by the pivot bolt 39 which passes through the block 37 at right angles to the pivot bolt 36. The cable end fitting 40 of the cable 7 is secured between the links 38 by a pivot bolt which may be engaged with any pair of holes 42 in these two links 38 thereby providing a means of adjusting the effective length of the cable 7. The upper end of the cable 7 is provided with a forked end fitting 43 which may be secured to the eyebolt 8 which is fitted to a strong part of the fuselage frame of the aeroplane, or to the end of the sling 9 if the fuselage is of monocoque construction. This connection is made by the transverse pin 44 having a cranked handle 45 to facilitate its insertion and removal. Fig. 7 illustrates an alternative form of adjustment for the length of the cable 7 in which a double ended nut 46 engages with right and left hand screw threaded parts 47 and 48 secured to the cable 7 and the cable end fitting 40. Rotation of the double ended nut 46 will increase or decrease the effective length of the cable 7 according to the direction of rotation in the well known manner.

The forward ends of the cables 2 are fitted with

forked end fittings 50 which may be connected to anchorage plates 51 pivoted on the ends of the axles 52 of the undercarriage wheels 3 and secured by the nut 53 as shown in Figs. 4 and 5. The forked end fitting 50 may be secured to the anchorage plate by a nut and bolt or preferably by a quickly releasable pin 54 having a cranked handle 55 similar to the pin 44 shown in Fig. 6 for securing the upper end of the cable 7.

10 In use the aeroplane is wheeled to a position over the tethering device and is turned into wind. The swivel plate 27 is turned round the base pillar 23 and the cable ends of the cables 2 are secured to the anchoring plates provided on the aeroplane 15 by means of the connecting pins 54. The forked fitting 43 at the upper end of the cable 7 is secured to the eyebolt 8 or the sling 9 by means of the pin 44. The engine of the aeroplane may then be started up and then run until suitably warmed 20 after which any of the usual tests may be carried out. When completed the engine is throttled down and the securing pins 44 and 54 may be removed and the aeroplane is ready to take off.

I claim:

25 1. A device for anchoring an aeroplane comprising a single tethering member adapted to be anchored to an aeroplane landing or storage surface, said means comprising a socket, a pin mounted in said socket, a cable having one end

30 secured to said pin and the other end adapted to be secured to a forward part of an aeroplane to take the forward thrust, a second cable having one end secured to said pin and the other end adapted to be secured adjacent the tail end of the 35 aeroplane, said tail anchoring cable being shorter than said other cable whereby the socket is necessarily positioned adjacent the tail end of the aeroplane, thereby preventing the tail from rising.

2. An anchoring device as recited in claim 1 in 40 which the socket is disposed vertically in the center of an open work cage, and means to secure said cage to said fixed landing or storage surface.

3. An anchoring device as recited in claim 1 in 45 in which said socket is provided with a multiplicity of transverse projecting rods enabling it to be embedded in said landing or storage surface.

4. An anchoring device as recited in claim 1 in 50 which said forward extending cable is fixed to a collar surrounding said rotatable pin.

5. An anchoring device as recited in claim 1 in 55 which the free ends of said cables are provided with means for rotatably coupling them to parts of said aeroplane.

JAMES MARTIN.
